US00D989300S

(12) **United States Design Patent** (10) Patent No.: **US D989,300 S**
Newton et al. (45) Date of Patent: ** Jun. 13, 2023

(54) **CONNECTOR FOR VTE PREVENTION PUMP**

(71) Applicant: **Arjo IP Holding AB**, Malmö (SE)

(72) Inventors: **Michael David Newton**, Boerne, TX (US); **David John Cain**, Houghton Regis (GB); **Stephen Howells**, Cardiff (GB); **Richard Keogh**, Cardiff (GB)

(73) Assignee: **Arjo IP Holding AB**, Malmö (SE)

(**) Term: **15 Years**

(21) Appl. No.: **35/512,787**

(22) Filed: **Apr. 19, 2021**

(80) **Hague Agreement Data**

Int. Filing Date: **Apr. 19, 2021**

Int. Reg. No.: **DM/214021**

Int. Reg. Date: **Apr. 19, 2021**

Int. Reg. Pub. Date: **Oct. 22, 2021**

(51) **LOC (14) Cl. 24-02**

(52) **U.S. Cl.**

USPC **D24/129**

(58) **Field of Classification Search**

USPC **D24/129, 127**

CPC **A61M 25/00; A61M 39/00**

See application file for complete search history.
